UNITED STATES PATENT OFFICE.

PAUL E. BRENEMAN, OF DETROIT, MICHIGAN, ASSIGNOR TO C. R. WILSON BODY COMPANY, OF DETROIT, MICHIGAN, A CORPORATION OF MICHIGAN.

METALLIC VEHICLE BODY.

Application filed November 10, 1919. Serial No. 336,786.

To all whom it may concern:

Be it known that I, PAUL E. BRENEMAN, a citizen of the United States of America, residing at Detroit, in the county of Wayne 5 and State of Michigan, have invented certain new and useful Improvements in Metallic Vehicle Bodies, of which the following is a specification, reference being had therein to the accompanying drawings.

10 The invention relates to vehicle bodies of that type employing metallic frames, and the invention consists in the novel features of construction as hereinafter set forth.

In the drawings:

15 Figure 1 is a bottom plan view of the body;

Figure 2 is a cross-section thereof;

Figure 3 is a side elevational view partly in section;

20 Figure 4 is a view showing the joint connection.

In the construction of metallic bodies for vehicles it is usual to provide a body frame, including sills at the base conforming to 25 the contour of the body, and posts and other uprights extending upward from said sills. The body is supported upon the chassis frame, but inasmuch as the contour of the body seldom conforms to that of the chassis, the sills of the former have only a 30 limited contact with the sills of the latter. It is one of the features of the present invention to obtain a construction in which the sills of the body are superposed on the 35 sills of the chassis throughout their length, thereby affording better support. Other features of the improvement will be referred to more specifically hereinafter.

As shown, A and A' are the body sills, 40 which are spaced from each other to correspond to the spacing of the chassis sills. These sills A are formed of any suitable structural shape, but as shown are inverted channels A² having foot flanges A³ projecting oppositely from the lower ends thereof. B is the sheet metal body which is connected 45 to the sills A and A' by bottom panels C, also formed of sheet metal, and extending outward from the sills and terminating at their outer edges with down-turned flanges D. These flanges D are connected to the 50 body sheets preferably by forming the latter with return-bent lower edges E, thereby forming a seam and a reinforcement.

Instead of forming the body B of a single 55 integral section, it is preferably formed of a plurality of sections which are united to each other by the sills A and A'. Thus as shown, the body is formed of three units F, F' and F² respectively arranged at the front, 60 in the center and at the rear. Each unit has a cross bar G which rests upon the sills and carries the load of the body thereinto, said cross-bar also forming a support for the seat and the load carried thereby. 65

With the construction as thus far described, it will be observed that the sills A are adapted to rest upon the chassis sills H throughout their length and are connected thereto by any suitable means, such as the bolts I. These same bolts secure the bottom panels C to the sills A and thereby hold the several units in fixed relation to each other. To support the units before they are mounted upon the sills, each is preferably provided with one or more members J riveted, spot-welded, or otherwise secured to the panels C and projecting downward a distance greater than the depth of the flanges D and E, so as to protect the edge 80 of the unit from marring. 75

One of the principle advantages of metallic frame bodies is due to the fact that such bodies may be placed in enameling ovens and subjected to a temperature which would 85 be injurious to wooden frames. On the other hand, for trimming the body wood is advantageous, because of permitting tacking. With my improved construction the body units, which are subjected to the finishing 90 process when placed in the ovens, are formed entirely of metal, but in completing the structure wood fillers are employed where advantageous for finishing or reinforcement. Thus as shown, K is a filler block which 95 extends between the panels C and the door opening L. Also the floor between the sills is formed of wooden boards M, which are supported at their opposite ends upon the foot flanges A³. Where the unit sections are mounted in relation to each other, it is desirable to form a flushed joint. This I 100 accomplish by turning inward the flanges N at the edges of each unit, which abut against each other and to hold these flanges from displacement the wooden inserts K are grooved, as indicated at O, to receive the same. 105

The construction is one which is particularly adapted for quantity production at small expense.

What I claim as my invention is:

- 5 1. A metallic body for vehicles, comprising sills independent of the chassis frame arranged to be directly superposed thereon, a body shell of a contour differing from that of the sills, and members projecting laterally from said sills for supporting the body shell.
- 10 2. A metallic vehicle body, comprising body sills arranged to register with the sills of the chassis frame, a body shell of a contour differing from that of said sills, and panels extending laterally outward from said sills and connected to the lower edge portion of said body shell.
- 15 3. A metallic vehicle body, comprising body sills arranged to register with the sills of the chassis, an over-hanging body shell differing in contour from that of the sills, a metallic panel extending between the sill and over-hanging body shell attached to
- 20 25 the lower edge portion of the latter and

forming a support therefor and a portion of the floor, and a complementary floor extending between the sills.

4. A metallic vehicle body, comprising a sill for registering with the sill of the chassis, an over-hanging body shell, a metallic panel extending from said sill outward to said body shell and provided with a depending flange at its outer edge, to which said body is attached. 30

5. A metallic vehicle body, comprising a sill for registering with the sill of the chassis, an over-hanging body shell, a metallic panel extending outward from the top of the body sill and provided at its outer end with a depending flange attached to said over-hanging body shell, and a member depending from said panel a greater distance than said depending flange forming a support for said body when detached from the chassis and protecting the outer lower edge from injury. 40

In testimony whereof I affix my signature.

PAUL E. BRENEMAN.
